(57) **CLAIM**

I claim the ornamental design for a golf bag bottom, as shown and described.

DESCRIPTION

FIG. 1 is a perspective view of a golf bag bottom showing my new design;

FIG. 2 is a front elevation view of the golf bag bottom shown in FIG. 1;

FIG. 3 is a top plan view of the golf bag bottom shown in FIG. 1;

FIG. 4 is a rear elevation view of the golf bag bottom taken from the top in FIG. 3;

FIG. 5 is a bottom view of the golf bag bottom shown in FIG. 1;

FIG. 6 is a side elevation view of the golf bag bottom taken from the left in FIG. 3; and,

FIG. 7 is an opposite side elevation view of the golf bag bottom taken from the right in FIG. 3.
